UNITED STATES PATENT OFFICE

2,452,617

GAS OPERATED SHOULDER WEAPON

Joseph W. Wechsler, New York, N. Y.

Application July 23, 1945, Serial No. 606,696

10 Claims. (Cl. 89—140)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to firearms and more particularly to automatic military rifles. It is specifically concerned with improvements in a rifle of the type described and illustrated in Patent No. 2,377,338, issued June 5, 1945, to J. C. Garand for Firearm.

The M1 rifle is a gas-operated, clip-fed, air-cooled, semi-automatic (self-loading) shoulder weapon. By "semi-automatic" is meant capable of performing, after firing, the functions of extracting and ejecting the empty cartridge case, cocking the hammer, and reloading preparatory to refiring. For refiring, the trigger must be released and again pulled. Similarly, the trigger must be separately actuated for each shot.

The semi-automatic feature of the rifle imposes a limitation rendering such rifle inadequate for certain uses. If this limitation were removed, the field of use of the rifle would be significantly widened.

Accordingly, it is an object of this invention to provide a firearm capable of delivering uninterrupted fire automatically and at a high rate so long as the trigger is held back and ammunition is available in the magazine or clip. Another object is to provide a firearm which will deliver fire either semi-automatically or completely automatically at the will of the operator.

A further object is to provide a mechanism which may readily be installed in existing rifles similar to those of Patent 2,377,338 to convert them to full-automatic weapons selectively semi-automatically operable.

With these and other objects in view, as will hereinafter more fully appear, reference is made to the accompanying drawings showing one embodiment of the invention. In the drawings:

Figure 1 is a fragmentary right side view of a rifle in accordance with the invention with parts broken away and showing the selector in position for automatic fire;

Figure 2 is a view similar to Fig. 1 showing certain of the parts in alternative positions;

Figure 3 is a partial sectional view taken on the plane of the line 3—3 of Fig. 1;

Figure 4 is a partial sectional view, partly in top plan, taken on the plane of the line 4—4 of Fig. 1;

Figure 5 is an exploded view in perspective of certain modified and additional parts to be in-

2

corporated in existing rifles for the practice of the invention;

Figure 6 is a view similar to Fig. 2 showing the selector in position for semi-automatic fire; and

Figure 7 is a sectional view taken substantially along a plane as indicated by the line 7—7 of Fig. 1.

For constructional details of parts not shown and for a complete description of the operation and functioning of the rifle, upon which for purposes of illustration the present invention is based, reference may be had to the aforementioned Patent No. 2,377,338.

Referring more particularly to the drawings, 15 where like reference characters designate like or corresponding parts throughout the several views, 8 designates generally the receiver of such rifle, 10 designates generally a trigger housing group, and 11 the operating rod which is gas-

20 propelled rearwardly and which is spring biased forwardly by means, not shown, conventional in the rifle. The operating rod 11 is provided with finger hold 12 by means of which it may be manually actuated and the rear part of the op-

25 erating rod 11 is movable in a guide groove 13 which is formed in the right hand side of the receiver 8. The operating rod 11 is connected to the rifle bolt 14 in a conventional manner and moves the bolt rearwardly, when the operating

30 rod is actuated by the gas pressure, for extracting and ejecting a cartridge case, not shown, and also moves the bolt 14 forward, when it is spring biased forward by its operating rod spring on counter-recoil for chambering another round of ammunition. A hammer is mounted in the trigger housing group 10 on the pivot 16, in the conventional manner, and said hammer 15 is en-

35 gaged by the bolt 14 upon rearward movement of the bolt for moving the hammer rearwardly and downwardly to a cocked position. A trigger 17 is pivotally mounted on a pin 18 and has a sear 19 pivotally connected thereto, just above the trigger pivot 16. The hammer 15 is provided

40 with a pair of rear claws or hooks 20 which are engaged under the sear 19, when the hammer is moved to a cocked position by the bolt 14, as just previously described. The trigger 17 is provided with a pair of laterally projecting lugs 21, at the upper end thereof which, when the trigger 17 is

45 in a released position, are disposed to engage the forwardly projecting hooks or lugs 22 on the hammer 15. The hammer 15 is spring biased upwardly and forwardly by hammer spring 23 which bears against a hammer spring plunger 55 24, which in turn seats in a notch in the hammer

15, above its pivot 16. The hammer spring 23 is seated in a housing 25 having a bifurcated, closed rear end which is loosely pivoted on the trigger pivot 18 and which yieldably bears against the forward part of the sear 19, for normally holding the upper engaging portion of the sear 19 in a forward, operative position.

The sear 19 normally catches and holds the hammer 15 cocked after firing of the piece and before the trigger 17 can be released. When the trigger 17 is released, the lugs 21 are moved into the path of the hooks 22 and thereafter and before the trigger is fully released the sear 19 is moved out of engagement with the rear hammer hooks 20 by the rearward movement of the upper portion of the trigger 17, which bears against the sear 19, so that after the release of the trigger 17 hammer 15 is held in a cocked position only by engagement of the trigger lugs 21 with the forward hammer hooks 22.

The parts previously described, their assembly and coaction and their operation are all conventional to the rifle and have been illustrated and described merely to better illustrate one employment of the attachment, designated generally 26, and which includes a pair of angular guide brackets 27 having upwardly extending studs 28 which engage recesses 29 in the under side of the portion of the receiver 8, which forms the operating rod guide 13. The guide brackets 27 are retained in place by means of their depending blades 30 which engage screws 31, which are removably secured in a side plate of the rifle. A sear trip lever actuating slide 32 is reciprocably supported by the guide brackets 27 against the under side of the receiver guide groove 13. Slide 32 at its forward end is provided with an upturned lug or detent 33 which is disposed in a recess 34 of the receiver 8, which opens into the guide groove 13, which constitutes a modification of the receiver 8 and which is provided to accommodate a portion of the attachment 26. The lug 33 extends into the forward part of the guide groove 13 and is disposed to be engaged by the forwardly facing shoulder 35 on the operating rod 11, as said operating rod approaches the forward extremity of its movement for imparting a forward movement to the slide 32. The slide 32, at its opposite, rear end, is provided with an elongated looped portion 36 which is substantially wider than the body of the slide 32. The looped portion 36 projects laterally from one side wall of the slide 32 and the exposed portion of the loop 36 is engaged by a spring backed plunger 37 which, together with its spring 38, is mounted in a recess 39 in the receiver 8, as best seen in Fig. 3. Plunger 37 by engagement with loop 36 urges slide 32 rearwardly and against the shoulder 35.

A sear trip lever, designated generally 40, is pivotally mounted, intermediate of its ends, on a pin 41 which extends through a yoke 42. Yoke 42 is provided with a stem or shank 43 which slidably engages a longitudinally disposed bore 44 in a plate of the receiver 8, as best seen in Fig. 4. The receiver 8 is also provided with a cylindrical bore or recess 45 which opens outwardly of the right side thereof, and into which the forward end of the bore 44 opens. The right side of the rifle stock 46 is provided with a recess adapted to receive a selector latch plate 47, by means of the screw fastenings 48. A selector, designated generally 49, includes a shaft 50 having an integral crank 51 at one end thereof. Shaft 50 is rotatably mounted in the bore 45 and is provided with an eccentric portion 52, adjacent

the opposite end thereof, against which the forward, inner end of the stem 43 bears, as seen in Fig. 4. The crank 51 provides means for rotating the shaft 50 180° for moving the eccentric portion 52 from a rearward, operative position, as seen in Fig. 4, to a forward position within the bore 45 which will permit a forward movement of the stem 43, for a purpose which will hereinafter be described. Selector plate 47 is provided with a pair of arcuately shaped spring arms 53 having embossed angular detent portions 54. Spring arms 53 have their free ends spaced apart to form a passage 55. The arms 53 are all set outwardly with respect to an inwardly offset portion 56 of the plate 47. The passage 55 is provided to permit insertion of the crank 51 therethrough, and said crank is adapted to be oscillated beneath the upper or free end portions of the arms 53, through an arc of approximately 180°, for displacing the eccentric 52 forwardly or rearwardly. Crank 51 is provided with a notched portion 57 which engages one of the detent portions 54 at one extremity of its movement, and the other detent portion 54 at the other extremity of its 180° movement, for latching the selector 49 with its eccentric 52 in either a forward or rearward position.

Lever 40, at its upper end, is provided with a laterally projecting pintle 58 which loosely engages in the loop 36 for pivotally connecting the upper end of lever 40 to the rear end of slide 32. A sear trip bar 59 is provided with a restricted shank 60 at its forward end, which extends into and reciprocally engages a guide recess 61 in a plate of the receiver 8, and which is disposed beneath the bore 44. Guide recess 61 opens rearwardly, and sear trip 59 projects rearwardly therefrom and is provided with an enlarged concave shoulder 62, at its rear end, which engages a laterally projecting lug 63 on the upper part of the sear 19. The lug 63 constitutes a modification of the sear 19. The sear trip bar 59, adjacent its guide shank 60, is provided with a vertical opening 64 into which the lower, tapered end 65 of the lever 40 loosely extends.

From the foregoing it will be apparent that when the selector 49 is moved to its position of Figs. 1, 2, and 4, the attachment 26 will be in an operative position for converting the rifle, from a semi-automatic, to a full automatic firearm. With the parts thus disposed, the yoke 42 will be held in its rearmost position by the eccentric 52 being displaced rearwardly, as seen in Fig. 4, to provide an abutment for the forward end of the shank 43 to hold the yoke 42 in its rearward position. With the parts thus disposed, the plunger 37 is bearing against the loop 36 for urging the slide 32 rearward, and with the operating rod 11 out of engagement with the lug 33, the pressure of the hammer spring 23 on the detent 19 is sufficient to urge the sear trip 59 forwardly enough so that the sear 19 can engage and latch the hammer 15 in a cocked position, when the operating rod 11 and bolt 14 move to the rear after a round has been fired. As the trigger 17 has been pulled rearwardly in order to fire a round from the piece, its lugs 21 are displaced forwardly and out of the path of movement of the forward hammer hooks 22. As the operating rod and bolt 14 move forward and as the operating rod approaches the forward extremity of its movement, the slight movement of the operating rod 11 which occurs after the bolt 14 has returned to battery and been locked, constitutes the movement during which the shoulder 35 of the operating rod 11 engages the

lug or detent 33 to move the slide 32 a slight distance forward. This forward movement of the slide 32 rocks the lever 40 clockwise from its position of Fig. 1 to its position of Fig. 2. This slight clockwise rotation of lever 40 produces a sufficient rearward movement of the sear trip bar 59 to rock the sear 19 sufficiently on its pivot and against the action of the hammer spring 23, to move the sear 19 out of engagement with the rear hammer hooks 20 to release the hammer 15 therefrom. As this occurs almost instantaneously and while the trigger 17 is still held rearwardly in the position as seen in Fig. 1, the hammer will thus be caused to fall automatically to strike the firing pin, not shown, to fire the round, not shown, which was chambered by the bolt 14 on its forward, counter-recoil movement to produce a complete automatic functioning of the piece. The entire cycle previously described will, of course, be repeated by the hammer falling on the firing pin so that the rifle will continue to fire automatically until the trigger 17 is released or the supply of ammunition contained in the firearm is exhausted.

In order to render the attachment 26 inoperative so that the piece can be fired semi-automatically or in its conventional manner, it is only necessary to rotate the selector crank 51 upwardly and forwardly through an arc of 180° from its position of Figs. 1 and 2 to its position of Fig. 6. This will rotate the selector shaft 59 one-half turn to displace the eccentric 52 forwardly and out of engagement with the forward end of the shank 43. Consequently, the forward pull exerted on the slide 32 by the operating rod 11, in approaching its forward position, will cause the lever 40 to be moved forward at its pivot point to its position of Fig. 6, thus moving the trip bar 59 forwardly sufficiently to disengage it from the sear lug 63. As a result, the next time that the operating rod 11 is moved rearwardly, the plunger 37 will cause the slide 32 to move rearwardly relatively to the pintle 58, said movement being accommodated by the elongation of the opening in the loop 36 through which pintle 58 extends. Consequently, upon forward movement of the operating rod 11 in counter-recoil, said rod, at the extremity of its forward movement, will move slide 32 forward relatively to the pintle 58 so that no movement of the lever 40 or trip bar 59 will result and, consequently, the piece will then function in its well-known semi-automatic manner. While the invention has been described as an attachment since it is intended to be applied to the rifles already manufactured, it will be obvious that it can constitute an integral part of the rifles manufactured in the future, so that such rifles will be selectively full automatic or semi-automatic.

Various modifications and changes in the construction and arrangement of the parts forming the invention are contemplated and may obviously be resorted to, and said invention is likewise adapted for use with other types of semi-automatic firearms without departing from the spirit and scope of the invention as hereinafter defined by the appended claims.

I claim:

1. In a rifle having a sear, the combination of an operating slide slidably mounted in the rifle and having a detent adapted to be engaged by a reciprocating part of the rifle as said part approaches its forwardmost position for moving the slide forwardly on the rifle, means on the

rifle for pivotally mounting the lever intermediate of its ends, means operatively connecting one end of the lever to the slide, and a connecting rod reciprocably mounted on the rifle, and means connecting said rod to the opposite end of the lever and adapted to bear against the rifle sear to move the same to an inoperative position when the slide is moved forwardly for imparting rearward movement to the connecting rod through the lever.

5 2. An attachment as in claim 1, wherein the means on the rifle pivotally mounting the lever includes a stem slidably mounted lengthwise of the rifle, and a selector means for moving and holding the stem in an operative or inoperative position, whereby said stem can be moved to and held in an inoperative position for preventing actuation of the sear by the operating rod when moved forwardly.

10 3. An attachment as in claim 1, wherein the means on the rifle pivotally mounting the lever includes a stem slidably mounted lengthwise of the rifle, and a selector means moving and for holding the stem in an operative or inoperative position, whereby the sear will not be actuated by the forward movement of the operating rod when said stem is in an inoperative position, said selector means including an eccentric portion against which the forward end of the stem bears and a crank connected to the eccentric for turning the eccentric to displace it forwardly to free the stem for forward displacement of the shaft.

15 4. An automatic fire attachment for a rifle, comprising a pair of slidably mounted rods, and a pivotally mounted lever connected to the adjacent ends of said rods to cause the rods to move in opposite directions, one of the rods having a portion adapted to be engaged by an operating part of the rifle to impart forward movement to said rod to thereby cause rearward movement of the other rod through said lever, and said last mentioned rod, when moved rearwardly, engaging a movable rifle part for holding the same inoperative.

20 5. An attachment as in claim 4, a yoke on which said lever is pivotally mounted, said yoke being reciprocably mounted for lengthwise movement relatively to the rifle, said attachment being inoperative when the yoke is in a rearward position, and selector means for displacing the yoke rearwardly to render the attachment inoperative.

25 6. In a gas operated semiautomatic rifle having a bolt, an operating rod which is gas propelled for moving the bolt rearwardly for extracting and ejecting a cartridge case and spring biased forwardly for chambering a new round and for locking the bolt in battery position, a hammer disposed in the path of movement of the bolt and recocked by the rearward movement thereof, a sear engaging and holding the hammer in a cocked position and a trigger having lugs disposed in the path of movement of the hammer, when the trigger is released, said lugs being movable out of the path of movement of the hammer when the trigger is retracted; an automatic attachment for the rifle, comprising the combination of a lever pivotally mounted on the rifle and intermediate its ends, a slide connected to one end of the lever and having a portion disposed in the path of forward movement of a part of the operating rod and engaged and moved forward by

30 70 the operating rod as it approaches the forward extremity of its movement, and a sear trip bar slidably mounted lengthwise on the rifle and connected to the opposite end of the lever and moved rearwardly by the forward movement of the slide, said sear trip bar engaging and moving the sear

to a released position whereby the hammer is released from engagement with the sear when the sear trip bar is moved rearwardly.

7. An attachment as in claim 6, a yoke in which the lever is pivotally mounted, said yoke being mounted in the rifle for movement forwardly and rearwardly of the rifle for rendering the attachment inoperative or operative, respectively.

8. An attachment as in claim 6, and selector means including a yoke for pivotally mounting the lever, said yoke having a stem mounted in the rifle for forward and rearward movement, and a manually operable forwardly and rearwardly displaceable abutment for engaging the forward end of the stem for rendering the attachment operative, when the abutment is displaced to rearwardly, and inoperative, when the abutment is displaced forwardly relatively to the rifle.

9. An attachment as in claim 6, said attachment also including selector means having an abutment movable forwardly of the rifle to render the attachment inoperative, and rearwardly to render the attachment operative, said selector means including a manually actuated operating crank, and a latch plate for holding the crank in a plurality of adjusted positions.

10. In a gas operated automatic and semi-automatic firearm having a bolt, an operating rod connected to the bolt and which is gas propelled rearwardly for opening the bolt for extracting and ejecting a cartridge case and spring biased forwardly for chambering a new round and for locking the bolt in battery position, a trigger, a sear pivotally mounted on the trigger, a hammer disposed in the path of movement of the bolt and engaged thereby, on the rearward movement of the bolt, and moved to a cocked position, said hammer being engaged and held by the sear, when moved

to a cocked position, said trigger having lugs disposed in the path of movement of the hammer, when the trigger is in a released position, and out of the path of movement of the hammer when the trigger is retracted, said trigger functioning to release the sear from the hammer, when the trigger is released, to cause the trigger lugs to engage the hammer so that the firearm will function semi-automatically to fire when the trigger is released and again pulled; the combination of a slide having an elongated slot and actuated by the forward movement of the operating rod, a yoke means slidably mounted in the rifle, a lever pivoted on said yoke and having a pin extending through the elongated slot, a trip bar adapted to disengage the sear from the hammer, while the trigger is in a retracted position, to cause full automatic operation of the firearm, said trip bar having an opening, said lever having a projection within said opening, and manually operable means whereby said yoke means may be displaced forwardly of the rifle and thereby said trip bar.

JOSEPH W. WECHSLER.
